UNITED STATES PATENT OFFICE.

ETHAN I. DODDS, OF ZELIENOPLE, PENNSYLVANIA, ASSIGNOR TO KERNER MANUFACTURING COMPANY, OF PITTSBURGH, PENNSYLVANIA, A CORPORATION OF PENNSYLVANIA.

METHOD OF MAKING BOLTS.

1,131,343.

Specification of Letters Patent. Patented Mar. 9, 1915.

Application filed June 26, 1914. Serial No. 847,453.

To all whom it may concern:

Be it known that I, ETHAN I. DODDS, a citizen of the United States, residing at Zelienople, in the county of Butler and State 5 of Pennsylvania, have invented a new and useful Improvement in Methods of Making Bolts, of which the following is a full, clear, and exact description, reference being had to the accompanying drawings, forming

10 part of this specification, in which—

Figure 1 is a perspective view of one form of blank which can be used for making bolts by my improved process; Fig. 2 is an end view of the shearing dies with a blank in 15 position; Fig. 3 is a similar view showing the dies after shearing the blank; Fig. 4 is an end view of a re-shaping die showing the blank after it has been returned to its initial shape; Fig. 5 is a side elevation of a blank 20 after it has been sheared by the die shown in Fig. 3; Fig. 6 is a side elevation of the finished bolt and Fig. 7 is a sectional view on the line VII—VII of Fig. 6.

This invention relates to an improved 25 method of making bolts, and particularly for making stay-bolts for locomotive boilers.

The precise nature of my invention will be best understood by reference to the accompanying drawings, which will now be 30 described, it being premised, however, that various changes in the apparatus as well as the steps of the process may be made, without departing from the spirit and scope of my invention as defined in the appended 35 claims.

In the drawings, 2 indicates the blank, which is placed between shearing die members 3, as indicated in Fig. 2. These die members are then moved relatively to each 40 other to shear the blank, as indicated in Figs. 3 and 5. The blank is then inserted

between re-shaping dies 4, as shown in Fig. 4, to return the blank to its initial shape. The ends of the blank are then upset to form a head at each end which heads are then 45 screw-threaded, as indicated at 5 in Fig. 6. If desired, the bolt can then be twisted about the longitudinal axis, so that the sheared members will extend in a general spiral direction.

50

The advantages of my invention result from the provision of a cheap and efficient method of making bolts.

I claim:

1. The method of forming bolts, which 55 comprises the steps of shearing the body portion along a radial line by means of oppositely moving die members, and then restoring the blank to its initial shape, substantially as described.

2. The method of forming bolts, which 60 comprises the steps of shearing the body portion along a radial line by means of oppositely moving die members, restoring the blank to its initial shape, and then forming 65 securing heads on the ends of the bolts, substantially as described.

3. The method of forming bolts, which 70 comprises the steps of shearing the body portion along a radial line by means of oppositely moving die members, restoring the blank to its initial shape, then upsetting the heads on the ends of the blank, and then screw-threading said heads, substantially as described.

In testimony whereof, I have hereunto 75 set my hand.

ETHAN I. DODDS.
